COMBINED AEROSOL ACTUATOR AND DISPENSER FOR MEDICAMENTS

Herbert A. Goodwin, Sileby, England, assignor to Vantorex Limited, Loughborough, England, a British company

Filed Mar. 17, 1966, Ser. No. 1,511

Term of patent 14 years

(Cl. D83—1)

FIG. 1 is a front elevation view of a combined aerosol actuator and dispenser for medicaments, embodying my new design;

FIG. 2 is a side elevation view;

FIG. 3 is a back elevation view;

FIG. 4 is a bottom plan view;

FIG. 5 is a top plan view;

FIG. 6 is a perspective view; and

FIG. 7 is a fragmentary front view taken in the direction of line 7—7 in FIG. 2.

I claim:

The ornamental design for a combined aerosol actuator and dispenser for medicaments, substantially as shown and described.
